United States Patent Office.

RAPHAEL MORITZ SELDIS, OF NEW YORK, N. Y.

Design No. 3,946, dated March 29, 1870.

DESIGN FOR MUFFS.

The Schedule referred to in these Letters Patent and making part of the same.

To all whom it may concern:

Be it known that I, RAPHAEL MORITZ SELDIS, of the city of New York, in the county and State of New York, have invented a new and original Design for Muffs; and I do hereby declare that the following is a full, clear, and exact description thereof, which will enable others skilled in the art to make and use the same, reference being had to the accompanying drawing forming part of this specification.

The drawing represents a perspective view of the muff, provided with my design.

This invention relates to a new manner of arranging the different colors of fur on the outer sides of

muffs, and consists in the arrangement of alternate V-shaped courses of dark and light fur.

A, in the drawing, represents a muff of suitable kind, shape, and material. Its covering is made in alternate courses, *a b*, of white and "blue" fur, or light and dark material, the courses being V-shaped, as shown.

I claim as my invention—

The design for a muff, as shown.

RAPHAEL MORITZ SELDIS.
